(57) **CLAIM**

The ornamental design for a pet bed, as shown and described.

DESCRIPTION

FIG. 1 is a front, right and top perspective view of a pet bed showing my design.

FIG. 2 is a rear, left and bottom perspective view of a pet bed showing my design.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof.

FIG. 8 is a bottom plan view thereof; and,

FIG. 9 is an enlarged detail view of area 9 shown in FIG. 1. The broken lines in the drawing depict portions of the pet bed that form no part of the claimed design.

The dash-dot broken lines in FIG. 1 and FIG. 9 represent the boundaries and indicator of the enlarged view and form no part of the claimed design.
